Samuel House
Assignor to Hiram House
Parlor stove Design Patented August 31, 1852 -

Dec. 493

Samuel A. House of Mechanicville, N.Y.

Assignor to

Hiram House of Troy, N.Y.

Letters Patent No. 493 Dated Aug. 31st 1852

The schedule referred to in these Letters Patent and making part of the same.

To all whom it may concern:

Be it known that I, Samuel A. House of Mechanicville, in the County of Saratoga, and State of New York, have invented or produced a new and original design of front and top plates for parlor stove which I call the "Fairy Queen" and I do hereby declare that the following is a full, clear, and exact description of the same, reference being had to the annexed drawings, making a part of this specification, in which Fig. 1. is a direct view of the top. Fig. 2. is a sectional view of the top taken at the line x, y. fig. 3. is a view of the front plate & fig 4 a sectional view of the same, showing the curvature of the plate.

The ornamental design of the top of my stove

Des. 493

2

consists of the ornaments (a a) one on each side of the boiler hole in the top, and in the ornaments (b) & (c) also the moldings (d d) which form the edge and border of the top.

The ornamental design of the front plate consists of the ornamental bordering (e e) arranged on the sides and bottom, and in the ornament (f f) arranged on the panel at the top.

Having thus described my design of stone plates,

What I claim as new and desire to secure by

Letters Patent, is, the ornamental design and configuration of parlor stone top and front plates, the same as herein described, and represented in the annexed drawings.
